UNITED STATES PATENT OFFICE.

JAMES DENNEY JORDAN, OF OWENSBORO, KENTUCKY, ASSIGNOR TO THE KEN-RAD CORPORATION, OF OWENSBORO, KENTUCKY, A CORPORATION OF KENTUCKY.

THERMIONIC VACUUM TUBE.

Application filed January 16, 1926. Serial No. 81,684.

My invention relates to a construction of elements in a thermionic vacuum tube which makes the degree of vacuum obtained controllable.

5 It is a known fact that the degree of vacuum obtained in any vessel can never be better than that permitted by the vapor pressure of the various elements contained in that vessel. It is also a known fact that in obtaining a high 10 degree of vacuum the application of heat is necessary in order to liberate all volatile matter.

I have discovered a construction of elements which may be used in a vacuum tube which 15 permits the heating of the various elements involved, even to their melting point, without vaporizing the material used as a getter. The use of the word "getter" at this point, and throughout this specification, refers to any 20 material which is very active chemically and combines with residual vapors and gases in a vacuum tube producing a solid at the temperature and pressure used. It is readily seen that if elements are used with a relatively low 25 vapor pressure in the construction of the tube, the ultimate pressure obtained will be that of the vapor pressure of the particular getter used. As an example, a thermionic vacuum tube may be constructed with low vapor pressure 30 elements throughout and any convenient getter used. In this case the best vacuum obtainable will be represented by the vapor pressure of the getter or of the compounds formed by its action on the residual vapor not 35 removed by the pump.

If a construction is used such as described in this specification, the elements of the tube may be maintained at any desired temperature below the melting point of the elements 40 for as long a period as desired while the tube is connected to a vacuum pump. This heating process may consist of bombardment of the elements with electrons from the cathode or exposure to a high frequency electric field 45 which induces electric currents in the various elements producing the desired temperature. After the various elements have been denuded of volatile material in this manner the getter may be vaporized either by bombardment or by exposure to a high frequency electric field. In case the high frequency method is used 50 with the construction I have discovered the electric field must be in a direction preferably at right angles to the field used in the denuding process of the various elements.

By virtue of the properties of my construction of elements I have discovered that if a high frequency electric field is placed about the elements of the tube in a direction parallel to its axis the elements of the tube become hot, 60 while if this field is approximately perpendicular to the axis of the tube, and to the plane of the support to which the getter is attached, the getter will be vaporized without generating a high temperature in the elements 65 themselves.

My invention may be better understood by referring to the drawings which are annexed hereto and form a part of this specification, and which diagrammatically illustrate two 70 of the many possible applications of the principles involved.

Figure 1 represents a construction which may be used on tubes having elements lying in a parallel plane, or in parallel planes; while 75 Figure 2 represents a possible construction for tubes whose elements are cylindrical in shape and concentric.

Referring to Figure 1,

"A" represents the getter mounting, which 80 may be in the form of a wire as shown in the drawing or in the form of a sheet of material whose plane is parallel to the axis of the other elements of the tube;

"B" represents the cathode;

"C" represents the anode;

"D" represents the auxiliary third electrode, hereinafter referred to as the grid;

"E" represents the support wire for the cathode;

"F" represents the support for "E";

"G" represents that part of the glass structure through which the lead wires make entrance to the vacuum chamber. Throughout this specification this structure will be known 90 as the press;

"H" represents the flared glass tubing used in the manufacture of the stem;

"I" represents the tube through which the device is evacuated; and

"J" represents the glass bulb which forms the outer walls.

The small letters on Figure 2 refer respectively to the same elements as the large letters do in Figure 1.

Referring to Figure 1, the exhausting process may be carried out in accordance with the following schedule—

"I" should be connected to a suitable vacuum pump capable of exhausting to an abso- 110

lute pressure of approximately .001" of mercury or less. Heat should be applied to the bulb "J" until the temperature of this part of the device is at a point just below where 5 deformation occurs. An electric current should be passed through the cathode, which in this case is a wire, until its temperature is somewhat above that to which it will be subjected at any time during its life. A coiled 10 conductor carrying a high frequency electric current should be placed over the bulb in such a manner that its axis coincides with that of the bulb. With a suitable frequency and current in this coil the anode and grid may be 15 heated to the desired temperature which is just below the melting point of the material used in its construction. It will be noted that this last process does not generate heat in "A", the getter mounting. The getter mounting 20 "A" may be heated by conduction from the anode to a temperature just below that at which the getter vaporizes.

At this stage of the process, if the absolute 25 pressure inside the bulb is less than .001" of mercury, the exhaust tube may be melted off near the flare, thereby hermetically sealing the structure inside the bulb. In this state the high frequency coil may be held in such a position that its axis is perpendicular to 30 the plane of "A", the getter mounting, and with a suitable frequency and current heat will be generated in said mounting which raises the temperature of the getter to a point where vaporization occurs. The getter in its 35 vapor state being highly active chemically combines with the vapors which were not removed by the vacuum pump and forms solid compounds.

After this operation it is obvious that the 40 pressure on the inside of the vacuum chamber is equal to the vapor pressure of the construction material having the highest vapor pressure.

The foregoing process applies to a structure 45 made in accordance with Figure 2 or any other structure whereby the vaporization of the getter takes place subsequent to the heating of the elements.

The structure adapts itself readily to variations in the exhausting process. As an example, after the elements have been thoroughly denuded of foreign material the getter 50 may be vaporized before the vessel is sealed from the vacuum pump. In this case 55 the vapor acts as a flush forcing any other vapor which might be present out of the bulb. If this is done, however, sealing from the vacuum pump should take place immediately in order to eliminate oil and other vapors 60 from finding their way back into the tube.

My discovery permits the activation of the cathode by means of various activating mate-

rials which, if placed on the getter mounting represented by "A" Figure 1, may be vaporized at any convenient time during the manufacturing process by heating the getter mounting in the same manner as that described for vaporizing the getter itself. For example, a suitable filament may be used as a cathode and a very high degree of vacuum 65 obtained in the pumping process. A cutting length of this filament may be selected whereby the finished tube will be very deficient and the cathode an exceedingly poor emitter of electrons. If this same tube had a small 70 piece of activating material mounted on the getter mounting "A", and if same should be subsequently vaporized by any of the above mentioned heating processes, the vapor of the activating material would deposit on the 75 cathode and make a combination which would develop the cathode into an excellent electron emitter. In other words, the cathode can 80 thusly be made a more efficient emitter of electrons by using the activating material, 85 and same would consequently operate in service at a temperature considerable below that necessary, if no activating material had been used.

What I claim as new and desire to secure 90 by Letters Patent of the United States is:

1. A thermionic vacuum tube comprising an evacuated vessel, grid, filament and plate electrodes within said vessel and aligned with the vertical axis of said vessel, and a mounting for activating material within said vessel, said activating material mounting extending laterally across said electrodes in a substantially horizontal direction with respect to the vertical axis of said vessel and connecting with opposite sides of said plate electrode.

2. A thermionic vacuum tube comprising an evacuated vessel, a plurality of electrodes supported in axial alignment within said vessel, and a bridge member forming a support for activating material extending across one end of said electrodes and connected to opposite sides of said plate electrode.

3. A thermionic vacuum tube comprising an evacuated vessel, grid, filament and plate electrodes supported within said vessel in axial alignment, and an arch member supported from opposite sides of said plate electrode and extending across one end of said grid and filament electrodes, said arch member providing a support for activating material within said tube in a position substantially coincident with the central axis of said electrodes.

In witness whereof, I have hereto set my hand this the 12th day of January, 1926.

JAMES DENNEY JORDAN.
